UNITED STATES PATENT OFFICE.

WALTER E. ZANDER, OF PHILADELPHIA, PENNSYLVANIA, ASSIGNOR TO SCHLETTNER & ZANDER, INC., OF PHILADELPHIA, PENNSYLVANIA, A CORPORATION OF PENNSYLVANIA.

LADY'S HOSIERY.

Application filed March 16, 1925. Serial No. 15,750.

This invention, generally stated, relates to full fashioned hosiery and has more especial relation to so-called silk chiffon hosiery.

Silk chiffon hosiery, which is very popular at the present time, is of such fine texture throughout that the instep and foot portions are entirely too delicate to withstand even moderately hard usage. The result is that the leg portion is frequently in good order but the instep and foot portion condition renders the stocking useless for further wear. If the foot portion was reinforced according to well known methods of reinforce an unsightly line would appear at the juncture of the leg and instep portions of the stocking, which, since low shoes are almost exclusively now worn by women, is highly undesirable.

The leading object of the present invention is to overcome the above objectionable features and provide a silk chiffon stocking structure in which while all the delicate texture of the leg portion is preserved the foot and instep portions are efficiently reinforced in such manner that the regular web threads and the reinforcing threads form a fabric with parts blending one into the other in an artistic manner commensurate with the high grade of hosiery under discussion.

Other and further objects not at this time appearing will be referred to hereinafter.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in side elevation of a stocking embodying the invention.

Fig. 2, is a fragmentary view in front elevation thereof; and

Fig. 3, is a similar view in rear elevation thereof.

For the purpose of illustrating my invention I have shown in the accompanying drawings one form thereof which is at present preferred by me, since the same has been found in practice to give satisfactory and

reliable results, although it is to be understood that the various instrumentalities of which my invention consists can be variously arranged and organized and that my invention is not limited to the precise arrangement and organization of the instrumentalities as herein shown and described. 55

Hosiery embodying features of the present invention is knit upon a straight knitting machine equipped with apparatus as shown, described and claimed in U. S. Letters Patent numbered 1,198,482, dated September 19, 1916. In manufacture, the stocking web 10, which has salvage edges, is knit 60 in a well understood manner until after the narrowing operation has been completed as indicated at 11. The web as fabricated is of very fine grade of silk chiffon, a very popular material as at present employed. 70

At or shortly after the narrowing operation, as fancy indicates, carriers supplied with reinforcing thread are thrown into action for knitting into the web, simultaneously with web formation, a plurality of reinforced instep and ankle portions. Each carrier functions to knit reinforcing thread into the web in successive courses to cause the inner ends of the courses to define symmetrical, zig-zag-like lines 12 to provide a 80 reinforcing portion 13 of which there may be any desired number. For illustrative purposes I have shown four of such portions in the drawings. It is desirable, however, to have these reinforced portions at the instep and ankle parts of a stocking. The reinforced parts gradually increase in width as they approach the stocking foot. The stocking foot, heel, and toe parts are reinforced throughout and the reinforced instep 90 and ankle parts merge with the heel and foot reinforcement so that when low shoes or slippers are worn there is provided above the shoe line a plurality of spaced reinforced parts which gradually taper upwardly and are annularly disposed. Thus silk chiffon stockings may be manufactured to provide maximum wearing qualities at the toe, foot, and heel portions including instep and ankle portions without exposing a 95 marked degree of reinforcement above the shoe line. Since the reinforced parts may

be arranged in different designs many pleasing and ornamental effects may be obtained.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

1. A stocking having a leg portion of silk chiffon combined with a foot portion having a substantially continuous reinforcement at the instep extending well above the

upper edge of the usual low shoe, and merging into a plurality of ornamental upward projections.

2. A stocking having a leg portion of silk chiffon combined with a foot portion reinforced over substantially the entire instep and ankle with ornamental reinforced stripes projecting upward into the leg portion.

3. A stocking having a leg portion of silk chiffon combined with a foot portion reinforced over substantially the entire instep and ankle by ornamental reinforced areas projecting into the leg portion, two of said areas extending upward from the heel at opposite sides of the leg, and the combined width of said areas at the base being approximately equal to the width of the heel.

In testimony whereof, I have hereunto signed my name.

WALTER E. ZANDER.
